UNITED STATES PATENT OFFICE.

ALARD DU BOIS-REYMOND, OF PLON, NEAR KIEL, PRUSSIA, GERMANY, ASSIGNOR TO
THE FIRM SIGNAL GESELLSCHAFT M. B. H., OF KIEL, GERMANY.

SOUND APPARATUS.

Application filed March 24, 1921, Serial No. 455,321, and in Germany August 6, 1917.

In the construction of electromagnetically driven or operating sound apparatus, for example, electromagnetic submarine sound transmitters or receivers, the necessity often arises of fastening current coils of various kinds on the oscillating structures or systems of the apparatus. The invention is based on the recognition of the fact that the simple fastening of the coils on the oscillating structures or systems is unsatisfactory, in that the wires surrounded with insulating material form a loose structure in the acoustic sense which strongly damps the oscillatory system. Furthermore it is not feasible to calculate the magnitude of the additional masses made by the coils to the oscillating system.

An object of the invention is to remove the aforementioned difficulties. To this end special mechanical methods of fastening the coils on the oscillatory structures have been devised and will be hereinafter described in detail. The technical carrying out of the invention can be effected in different ways; either by building the coils themselves, and the oscillatory structures carrying them, together as a rigid mass, or by choosing a method of fastening the coils which obviates an acoustically injurious action of the same on the oscillatory structure. In the first case in the design of the oscillatory structure the additional mass formed by the coil must be taken into consideration. Other and further objects of the invention will appear or be pointed out hereinafter.

The rigid fastening above referred to is effected, for example, by casting the coil parts with binding material (resin, bakelite, or the like) so as to form a rigid structure, and then casting with suitable matrix in drilled grooves, slots or the like.

Suitable means for mounting the coils on the oscillatory structure or for mounting the coil carriers on the oscillatory structure for the purpose of acoustically insulating these parts may be effected by the interposition of non-rigid fastening means or intermediate layers with no appreciable elastic action or of such a nature as to form a structure tuned so low as to have a natural frequency much below the natural or coupling frequencies of the oscillatory structure or system. Thus, for example, the coils (to be hereinafter referred to) may be surrounded by or encased in such materials as rubber,

felt, velvet or the like as illustrated by acoustic insulating layer 12 in Figures 2 and 3. An illustration of the acoustic insulation of the coil carriers is had in the low tuned (or weak) springs 11 which cushion the carrier 9 for the choking coil 7 (to be hereinafter referred to in connection with Figures 2 and 3).

In the drawing several examples of construction of the invention are shown.

Figure 1 is an axial section of an oscillatory electromagnetic sound apparatus constructed in accordance with the principles of my invention and in which the interstices between the windings are filled in with suitable material for binding them together. The coil is thus cast in.

Figure 2 shows in section an electro-magnetic sound apparatus with a choking coil attached to the electromagnet system by springs.

Figure 3 shows in modified form an axial section at right angles to Figure 2 disclosing in detail the method of supporting the coil 5.

In Figure 1, 1 indicates a sound diaphragm, 2 and 3 the armature and electromagnet of an electromagnetically operating oscillatory structure, and 4 springs by which the parts 2 and 3 are connected with one another. 5 is the exciting coil which lies in slots in the field magnet 3 and is cast therein by means of an embedding mass 6.

According to the embodiment of my invention shown in Figures 2 and 3, an auxiliary apparatus may, when necessary, be mounted upon the vibratory structure without causing injurious damping effects. Thus, a choking coil 7 with a laminated iron core 8 is held by the carrier 9. The latter is guided on pins 10 which are rigidly seated in the field magnet 3, and is resiliently held by spiral springs 11. These spiral springs are of such resiliency that oscillations of the electro-magnetic vibratory structure are not transmitted to the choking coil; or, viewed in another way, the choking coil does not interfere with or affect the vibrations of the vibratory structure. As an additional acoustic insulating means, the choke coil together with the iron core carried by it engages against the carrier itself through soft layers 12 of indiarubber or the like. The exciting coils 5 of the electro-magnet are here divided into an alternating current coil and a

direct current coil, and in the current circuit of the latter the choking coil is connected.

The purpose of this construction will be readily understood. By an inspection of Figures 2 and 3, it will be seen that the construction is similar to that in a transformer having a closed magnetic circuit. In consequence strong alternating currents are induced in the direct current winding of the coils 5 by means of the alternating current winding of the same. Where the number of turns in the alternating current winding is less than the number of turns in the direct current winding, the induced currents in the latter may be very undesirable. By investigation, it has been found that the most advantageous results in the oscillating system are obtained when the number of turns in the direct current winding is made about ten times as great as the number of turns in the alternating current winding. Such a ratio in the numbers of turns in these windings, however, produces an alternating current potential in the direct current coil ten times as large as that in the alternating current coil and thus occasions a new difficulty. To overcome this difficulty, the choking coil 7 is connected up in circuit with the direct current winding for the purpose of confining the high voltages to those conductors which are disposed entirely within the casing 13. This is shown in Figure 2 where the wire 20 goes from the choke coil 7 to the winding 5 while the wire 21 connected to the other end of the winding 5 passes through the casing. The other lead 22 connects directly to the choke coil 7 so that the choke coil 7 and the direct current winding 5 are in series. As a result, the question of insulation as related to those wires which pass into and out of the casing becomes a comparatively simple one.

Another feature of the construction of Figures 2 and 3 is that all the operating parts are contained within a casing, a portion of the wall of which is formed by the diaphragm 1, and another portion of the wall of which is formed by the removable or detachable cap 13, and that these parts are carried or supported by the diaphragm 1 free from the cap 1. This feature of construction makes it possible to remove the cap without disturbing interior connections, so that inspection of the operating parts may readily be had.

55 I claim:

1. In acoustic apparatus, in combination, a vibratory diaphragm, a vibratory structure carried by said diaphragm, an electric coil, and means whereby said coil is carried by said vibratory structure but is acoustically insulated therefrom.

2. In acoustic apparatus, in combination, a vibratory diaphragm, a vibratory structure

in the form of an electro-magnet carried by said diaphragm, an electric coil, and means whereby said coil is carried by said electro-magnet but is acoustically insulated therefrom.

3. In acoustic apparatus, in combination, a vibratory diaphragm, a vibratory structure in the form of an electro-magnet carried by said diaphragm, a direct current polarizing coil for said electro-magnet, an alternating current exciting coil for said electro-magnet, a choke coil for said polarizing coil circuit, and means whereby said choke coil is carried by said electro-magnet but is acoustically insulated therefrom.

4. In acoustic apparatus, in combination, a vibratory diaphragm, a vibratory structure carried by said diaphragm, an electric coil, and means supporting said coil on said vibratory structure, said means being of such resiliency as to acoustically insulate the coil from said vibratory structure.

5. In acoustic apparatus, in combination, a vibratory diaphragm, a vibratory structure carried by said diaphragm, an electric coil, and means supporting said coil on said vibratory structure, said means having a natural frequency considerably below that executed by said vibratory structure, whereby the coil is acoustically insulated from said vibratory structure.

6. In acoustic apparatus, in combination, a casing, a vibratory diaphragm forming a portion of the wall of said casing, a removable cap forming the remaining portion of the wall of said casing and completely closing the apparatus, a vibratory structure carried by said diaphragm, an electric coil, and means whereby said coil is carried by said vibratory structure but is acoustically insulated therefrom; the said vibratory structure and coil being supported by said diaphragm free from the removable cap of said casing.

7. In acoustic apparatus, in combination, a casing, a vibratory diaphragm forming a portion of the wall of said casing, a removable cap forming the remaining portion of the wall of said casing and completely closing the apparatus, a vibratory structure in the form of an electro-magnet carried by said diaphragm, a direct current polarizing coil for said electro-magnet, an alternating current exciting coil for said electro-magnet, a choke coil for said polarizing coil circuit, and means whereby said choke coil is carried by said electro-magnet but is acoustically insulated therefrom; the said electro-magnet and coils being supported by said diaphragm free from the removable cap of said casing.

In testimony whereof I affix my signature.
ALARD DU BOIS-REYMOND.
